MACHINE FOR DIPPING AND WIPING BOX
TOE STIFFENERS
Lewis D. Bartley, 7 Spefford St., Newburyport, Mass.
Filed Jan. 9, 1963, Ser. No. 250,280
7 Claims. (Cl. 118—11)

This invention relates to a machine for dipping a piece of sheet material in a pool of liquid and wiping excess liquid therefrom as it is lifted from the pool. It is an object of the invention to provide a machine which accepts one by one sheet objects such, for example, as box toe stiffeners, dips the object in a pool of liquid to condition the object, wipes excess liquid therefrom and presents the object in a convenient position to be grasped. While not limited to any particular sheet object or conditioning liquid, the machine is hereinafter described as designed for dipping composition box toe stiffeners in a liquid which temporarily softens them so that they can readily be fastened with the other elements of shoe uppers.

For a more complete understanding of the invention, reference may be had to the following description thereof and to the drawings, of which

FIGURE 1 is a plan view of a machine embodying the invention;

FIGURE 2 is a side elevation of the same;

FIGURE 3 is a fragmentary sectional view, on a larger scale, taken on the line 3—3 of FIGURE 2;

FIGURE 4 is a fragmentary sectional view, on a larger scale, taken on the line 4—4 of FIGURE 1;

FIGURE 5 is an enlarged section on the line 5—5 of FIGURE 1;

FIGURE 6 is a section on the line 6—6 of FIGURE 5;

FIGURE 7 is a portion of FIGURE 6 with parts broken away to show in section, some of the parts being shown in a different position of operation; and

FIGURES 8, 9, 10 and 11 are portions of FIGURE 5, showing the parts in different positions of operation.

The machine illustrated on the drawings comprises a box 20, conveniently rectangular, in the bottom of which a pool 22 of liquid is maintained at a constant level by a bottle 24 of the liquid which is inverted in a receptacle 26 connected in the usual manner to the box 20. A pair of laterally elongated parallel gripper jaws 28, 30 are provided to seize a box toe stiffener W or the like, the jaws being carried by a pair of arms 32, 34, which revolve around the axis of a shaft 36. As indicated in FIGURE 6, the shaft 36 revolves in a fixed sleeve 38 which is secured to one side wall of the box 20 and extends part of the way toward the other side wall. The shaft 36 goes through both side walls of the box and is connected by a reducing gear in a gear box 40 to a motor 42, the motor being controlled by a micro-switch 44 which includes a plunger 46 spring-pressed to move from the retracted, switch-off position shown in FIGURES 1, 3 and 6 to the switch-on position shown in FIGURE 7. The end of the arm 32 is loose on the sleeve 38 but the end of the arm 34 is keyed to the shaft 36 so that when the shaft is rotated, the frame or yoke consisting of the arms 32, 34 and the jaws 28, 30 revolve with it.

When the moving parts are in their normal position of rest, the frame is in a substantially horizontal plane and the jaws 28, 30 are open and ready to receive the end of a box toe stiffener W as illustrated in FIGURE 5. The jaw 30 is rigidly secured to ends of the arms 32, 34. The jaw 28 is secured to ends of two arms 48, 50 which are respectively attached to the arms 32, 34 by pivots 52, 54. The arm 48 is short and is connected to the arm 32 by a tension spring 56 which tends to rock the arm 48 so as to move the jaw 28 close to the jaw 30 in order to grip an object between the jaws. The arm 50 is longer and carries

2

at its free end a cam follower 58 which rides on a fixed cam 60 attached to the fixed sleeve 38 to open the jaws as hereinafter described and to hold them open when the parts are in their normal position of rest. A stop element 62 is provided to ensure that after each revolution of the shaft 36 and the frame which is attached to it, the jaws will stop in the correct position of rest. The stop element is fixed on a vertical plate 64 within the box 20 which extends most of the way across the box 20 near the front wall thereof. The ends of the plate 64 are bent forward as at 66 and 68 for pivotal attachment to ears 70, 72 projecting from the inside of the front wall of the box 20. A spring 74 is provided to press the plate 64 toward its stopping position. A horizontal trigger plate 76 is secured to the upper edge of the plate 64 and projects out from the box. The bent end 68 of the plate 64 is narrowed and tapered, the terminal portion 78 being thickened and provided with a hole through which a pin 80 is slidably fitted. The pin 80 also passes through a short slot 82 in a side wall of the box 20 and has a conical tip 84 on its outer end which normally presses against the end of the plunger 46 to keep the switch 44 in the open or switch-off position. The pin 80 and plunger 46 are normally held in this position by a wedge cam 86 mounted on the arm 34. When the trigger is momentarily depressed by a touch of the finger, the plate 64 rocks to move the stop element 62 from under the jaw 30 and at the same time swings its bent end 68 to shift the pin 80 sufficiently in the slot 82 to move it out of alignment with the plunger 46, whereupon the plunger moves out to the switch-on position (FIGURE 7), starting the motor 42. This rotates the shaft 36 and the frame which is attached thereto. With the initial movement of the frame, the wedge cam 86 moves out of contact with the pin 80 so that when the return of the trigger plate 76 to its normal position shifts the pin laterally into alignment with the plunger 46, the pin 80 can shift inward and thus avoid pushing the plunger 46 to its switch-off position until the frame has nearly completed its revolution around the shaft 36. The initial movement of the frame also causes the cam follower 58 to ride off the cam 60, permitting the spring 56 to close the jaws 28, 30 on anything, such as a box toe stiffener, which has been inserted between them. The cam is thus inoperative until the revolution of the frame nears completion. The gripped article is then swung down through the pool 22 and around again to an inclined stationary table 90 which is supported by legs 92 secured to the sleeve 38. The table 90 is preferably corrugated, as indicated in FIGURE 4, so that the moistened work pieces will be less apt to cling to its surface. The table has a forward portion 94 which slopes down to proximity to the jaws 28, 30 when the jaws are in their normal position of rest. This forward portion 94 serves to guide fresh work pieces into the opening between the jaws and to prevent such work pieces from accidentally falling into the pool 22.

After a work piece W has been dipped by being pulled through the pool 22 by the jaws 28, 30, the excess liquid is wiped from the faces of the work piece by wiper plates 100, 102 which are supported over the rear portion of the pool and converge upwardly until their upper edges touch. The plate 100 is hinged at 104 to the bottom of the box 22 and is pressed toward the plate 102 by a spring 106. The plate 102 is pivoted between two fixed brackets 108, 110 extending down from the fixed sleeve 38. A spring 112 presses the plate 102 toward the plate 100. The plates 100, 102 are shaped and arranged so that their upper edges meet approximately in the circular path of movement of the jaws 28, 30. As is evident from FIGURE 6, the spacing between the arms 32 and 34 is

greater than the widths of the table 90, its forward extension 94 and the wiper plates 100 and 102. There is therefore no interference between the arms and these members when the jaws are swung with a work piece through a circular path around the axis of the shaft 36. The jaw 30 has a small saddle 114 of nylon or an equivalent mounted on its leading edge. This saddle serves to separate the mutually touching edges of the wiper plates 100, 102 when the jaws swing up between these plates, as shown in FIGURE 9, thus avoiding clash of metal on metal. The saddle then serves to separate a hinged cover member 116 from contact with the bend 118 between the table 90 and its extension 92. When the jaws have pulled the leading portion of the work piece W through the nip between the parts 116, 118, the cam follower 58 reaches a portion of the cam 60 which causes the jaws to open (FIGURE 11) releasing the work piece with its leading portion protruding from the nip between the parts 116, 118, in convenient position to be grasped by the operator. The cover member 116 is hinged at 120 to a larger cover 122 which in turn is hinged at 124 to the rear wall of the box 20. A spring 126 causes the member 116 to press yieldingly against the bend 118.

When the jaws have released the work piece as they near the completion of their revolution about the shaft 36, the wedge cam 86 on the arm 32 moves into contact with the inner end of the pin 80 which in the meantime has become aligned with the plunger 46 when the operator releases the trigger 74. The wedge cam 86 forces the pin 80 outward against the plunger 46. This opens the switch 44 and shuts off the motor 42 which coasts until the jaws are stopped in their correct normal position by the stop element 62. The contact with the element 22 is made by the nylon saddle 114, thus again preventing the clash of metal upon metal.

Recapitulating the cycle of operations, a box toe stiffener is placed on the guide 94 and slips down until a small part of it is between the jaws 28, 30. The operator presses on the trigger 74 which retracts the stop element 62 and causes the switch 44 to close, thus starting the motor 42. The cam follower 58 at once rides off the cam 60, permitting the spring 56 to close the jaws 28, 30 on the leading end of the box toe stiffener. The shaft 36 makes one quick revolution, swinging the box toe stiffener down through the pool 22, then up between the wipers 100, 102 to the table 90, the nylon saddle 114 serving to separate the wipers to let the jaws through with a minimum of noise. The saddle also lifts the cover member 116 from the topmost point of the table 90 to let the jaws pass between. When the jaws have passed beyond the topmost point of the table 90, the cam follower 58 engaging the cam 60 rocks the arm 50 to open the jaws and release the work piece, as indicated in FIGURE 11, leaving it in about the position indicated in FIGURE 5. When in this position the work piece is lightly held by the cover member 116 pressing it down on the topmost point of the table 90, the leading end of the work piece projecting forward in position to be easily grasped and withdrawn. After the jaws have been opened as described, they continue their motion until stopped by the engagement of the saddle 114 with the stop element 62. As the arms which carry the jaws approach their normal position of rest, the wedge cam 86 pushes the pin 80 and plunger 46 to close the switch 44. This completes the cycle and presents a dipped work piece to the operator, leaving the machine ready for the insertion of another work piece.

I claim:

1. Apparatus for conditioning pieces of sheet material, comprising a receptacle for a pool of liquid, a horizontal shaft in said receptacle rotatable above said pool, a frame swingable by said shaft in a circular orbit about the axis thereof, said frame including two laterally elongated jaws parallel to the axis of said shaft, spring means tending to close said jaws, a fixed cam mounted in said receptacle, means including a cam follower engaging said cam for holding said jaws open when said frame is in a normal

position of rest, said cam being shaped to permit said spring means to close said jaws immediately after a revolution of said frame starts from said position of rest and to keep the jaws closed until the frame has nearly completed its revolution, means for rotating said shaft, a stop member mounted on said receptacle normally in the path of said jaws and engaged by said jaws when in their normal position of rest, and a trigger member operable to move said stop member out of the path of said jaws whereby to release said jaws for a revolution.

2. Apparatus as described in claim 1, a stationary table above said shaft, means supporting said table within the orbit of said jaws in position to receive work pieces which have passed through the pool and wiping means.

3. Apparatus as described in claim 2, said table comprising two plates forming a ridge and diverging downwardly therefrom, the lower edge of one of said plates being adjacent to said jaws when the jaws are at rest, the other plate having a corrugated surface, a hinged cover member over said table, and spring means pressing said cover down on the ridge of said table.

4. Apparatus for conditioning pieces of sheet material, comprising a rectangular receptacle for a pool of liquid, said receptacle having front, rear and side walls, a horizontal transverse shaft journaled in the side walls of said receptacle, a frame swingable by said shaft about the axis thereof, said frame comprising two parallel arms extending radially with respect to the axis of the shaft and laterally elongated parallel jaws extending from one of said arms to the other and carried thereby, said frame having a normal position of rest in a substantially horizontal plane with said jaws adjacent to the front wall of the receptacle, an electric motor operatively connected to said shaft, a normally open switch mounted on a side wall of said receptacle to control said motor, a trigger member movably mounted on the front wall of said receptacle, said trigger member having a stop element normally in the path of and engaged by said frame when the frame is in its position of rest, means including a portion of said trigger member normally holding said switch in the switch-off position, said trigger member being manually movable to displace said stop element from the path of said jaws and permit said switch to close to the switch-on position whereby to swing said frame around the axis of the shaft, means operating to close said jaws at the beginning of a revolution about the shaft whereby to seize a work piece inserted between the jaws and to open said jaws to release the work piece as the frame approaches the completion of a revolution about the shaft, means on said frame operating to open said switch as said jaws approach said stop element in completing a revolution around the shaft, and means within said receptacle for wiping excess liquid from a work piece lifted from said pool by said jaws.

5. Apparatus as described in claim 4, and means for releasably holding a work piece after it has been dipped and wiped, said holding means comprising a table mounted in said receptacle over said shaft, said table comprising two plates forming a ridge and diverging downwardly therefrom, the lower edge of one of said plates being adjacent to said jaws when the jaws are at rest, the other plate having a corrugated surface, a cover member movably mounted over said table, and spring means pressing said cover member on said ridge of the table.

6. Apparatus as described in claim 5, one of said jaws having a small nylon saddle mounted on its leading edge to engage and separate said wiper plates and to engage and separate said cover member and the high point of said table when said frame is revolving.

7. Apparatus for conditioning pieces of sheet material, comprising a rectangular receptacle for a pool of liquid, a horizontal tubular sleeve secured to one side wall of said receptacle and extending part of the way to the other side wall, a shaft rotatably fitted in said sleeve and projecting through said other side wall, an electric motor operatively connected to said shaft, a frame swingable by said

shaft about the axis thereof from a normal position of rest, said frame comprising two parallel arms projecting radially from said shaft and respectively adjacent to said side walls of the receptacle and a pair of laterally elongated parallel jaws carried by said arms and extending from the end of one to the end of the other, one of said arms being secured to said shaft between said other side wall of the receptacle and the adjacent end of said sleeve, the other said arm loosely embracing said sleeve, a trigger member mounted on the inside of the front wall of the receptacle, means responsive to a movement of said trigger member to start said motor whereby to cause said frame to revolve about said shaft, and means carried by one of said arms for stopping said motor when the frame

approaches the completion of a revolution from its normal position of rest.
